UNITED STATES PATENT OFFICE.

KATHERINE SCHMUTZLER, OF GLENSIDE, PENNSYLVANIA.

APRON.

Application filed June 2, 1927. Serial No. 195,893.

The main object of this invention is to provide an apron which is useful for general purposes where it is desired to keep the clothing in a clean condition. The main purpose of this article is to provide suspenders which are secured to the apron proper and are so positioned and constructed so as prevent the suspender straps from slipping from the shoulders and thereby causing the apron to become disarranged and fall from place.

Another object of this invention is to provide an apron with properly positioned suspender straps which is inexpensive in cost, simple in construction and may be readily manufactured.

The above and other objects will become apparent in the description below in which characters of reference refer to like-named parts in the drawing.

Referring briefly to the drawing, Figure 1 is a perspective view of the apron in the position in which it is worn.

Figure 2 is a plan view of the apron laid out as in blank form.

Referring in detail to the drawing, the numeral 10 indicates a skirt of an apron. This skirt consists of a rectangular member of fabric or cloth and is provided with a button 11 at one of the corners near the upper edge of this skirt member. The blank of the apron skirt may be cut on the bias or otherwise to give any ornamental effect desired. The remaining upper corner of the skirt has a buttonhole 12 provided therein which cooperates with the button 11 at the opposite corner of the apron skirt and these two members are interengaged when the apron is draped on the wearer. The upper and lower longitudinally curved edges are slenderly curved so that they follow the waist line and skirt line of the wearer.

At two spaced apart positions on the upper edge 13 of the apron skirt suspender straps 14 and 15 extend upwardly at right angles to the longitudinal upper curved edge of the apron skirt 10. The upper ends of these suspender straps are joined by a semi-circular collar band 16 which is adapted to encircle the back of the neck and rest on the shoulders and suspend the entire apron from the same.

A band or strip 17 extends from the middle of the collar band 16 and when draped

over the body, this band follows the spine 55 of the wearer. The strip 17 is provided with a buttonhole 18 which is formed at the extreme end thereof and is adapted to engage the button 11 of the apron.

The skirt 10 of the apron is adapted to 60 completely envelope the skirt of the wearer when draped over the lower part of the body from the waist down. In fixing the apron in place on the body, the head of the wearer is slipped into the opening 19 between the 65 straps 14 and 15 and bounded at its upper end by the collar band 16. The entire apron hangs suspended from the collar band, the latter being provided to prevent the suspended straps 14 and 15 from slipping off the 70 shoulders of the wearer. The skirt 10 of the apron is secured in place by slipping the button 11 into the buttonhole 12. To retain the collar band 16 in arranged and comfortable position around the neck of the wearer 75 the strip 17 is projected from the curved collar band 16.

I claim:

1. An apron of the class described comprising an apron skirt adapted to hang from the waist downward and envelope the entire body, a button secured to one of the corners of said skirt, a pair of suspender straps integral with and projecting from said skirt, said skirt having a buttonhole formed in the 80 corner opposite to said button, a collar band joining the free ends of the suspender straps, and an additional strip projecting from the collar band having a buttonhole at its 85 extreme end for attaching said strip to the 90 button on the skirt.

2. An apron of the class described comprising an apron skirt curved at its upper longitudinal edge and adapted to enfold the entire body from the waist downward, the 95 curved edge of the skirt encircling the waist, a pair of spaced apart suspender straps integral with the skirt extending at right angles from the curved edge of the skirt, a curved collar band joined to the opposite 100 ends of the suspender straps, a strip extending outwardly from the collar band having a buttonhole formed therein at its outer end, a button mounted at one of the corners of the apron skirt, the opposite corner of said 105 skirt having a buttonhole formed therein.

In testimony whereof I affix my signature.
KATHERINE SCHMUTZLER.
